AUTOMATIC TURRET REVOLVING DEVICE

Charles M. Otis, Cincinnati, Ohio, and Alexander K. Dean, Rochester, N. Y., assignors to American Laundry Machinery Company, Cincinnati, Ohio, a corporation of Ohio

Application December 15, 1930, Serial No. 502,390

15 Claims. (Cl. 68—9)

Our invention relates to an ironing machine and, particularly, to an ironing machine embodying a plurality of forms extending radially from a single rotating member that is generally termed a turreting table and means for automatically moving the respective forms into and out of ironing position.

Heretofore, ironing machines of the above type have embodied a centrally located rotating member and a plurality of forms extending radially or diametrically outwardly therefrom but these devices have embodied no means for automatically moving the individual forms into and out of ironing position, such movement or racking of the forms being done by hand.

One object of our invention is to provide an ironing machine of the above type embodying operator operated means for controlling the movement of the forms into ironing relation with an ironing member after they have been moved into alignment therewith and automatically operating means controlled by the actuating mechanism for moving the forms into and out of ironing engagement with the ironing member for intermittently moving the respective forms disposed about the central rotating means into alignment with the ironing member.

Various other objects and advantageous features of our invention will be seen in the following description and one embodiment thereof may be seen in the accompanying drawings wherein similar characters of reference designate corresponding parts, and wherein:

Figure 1 is a plan view of an ironing machine embodying our invention; Figure 2 is a fragmentary view, partly in elevation and partly in section, showing the latching means for the turreting table and the main valve operating mechanism forming a part of our device; Figure 3 is a fragmentary plan view with the upper structure removed showing the turreting table revolving mechanism; Figure 4 is a fragmentary view showing the lever mechanism for operating an auxiliary valve which controls the rotation of the turreting table; Figure 5 is a diagrammatic view showing the fluid connections for operating the ironing machine, the cylinders and connections not being shown in true sectional arrangement but appearing as they are for clarity; Figure 6 is a sectional view showing the auxiliary valve in open position; Figure 7 is a perspective view showing the arrangement of the control means for the main operating valve of the device; Figure 8 is an end view partly in section and partly in elevation showing the ironing form 5

in two positions; namely, the full line position, when the ironing form is out of engagement with the ironing member; and the dot-dash line position, when the ironing form is in ironing engagement with the heated ironing member; and Fig. 9 is an elevational view of an ironing machine embodying our invention.

Referring to the drawings, we have shown one embodiment of our invention as comprising an ironing machine having a base 1 and a heated ironing member 2 mounted upon a support 3, the heated ironing member having the customary steam inlet 4. The ironing machine also consists of a plurality of forms or beds 5, there being two forms or beds in this instance each provided with a yoke pressing member 5'. One of these pressing members is shown disposed beneath the ironing member 2 and the other in a position to receive the goods to be ironed and the pressing members being mounted upon or joined to a rotating means 10 or turreting table 6 by means of radially extending arms 7. As shown by the dotted lines in Figure 1, one of the beds 5 is being moved out of alignment with the ironing member 2 and the other form which is diametrically disposed relative to the first form is being moved into alignment with the ironing member due to rotation of the turreting table 6 on which the beds are supported. The turreting table is disposed on a vertically extending pedestal 8.

Practically the entire mechanism for moving the beds 5 into alignment with the ironing member 2 is supported on the base 1, and the ironing member 2 is supported by uprights 9 at opposite sides of the base and in such position that the beds 5 will clear both of the uprights when moving into or out of alignment with the heated ironing member. In this instance, the turreting table 6 is not on a straight line between the uprights 9 but is disposed laterally 35 thereof.

As shown in Figure 3, the means for rotating the turreting table 6 and thereby moving the respective forms 5 into or out of alignment with the ironing member 2 consists of a cylinder 10 having a piston 11 therein, the cylinder being supported on the base 1 by a bracket 12. An exhaust conduit 13 leads from the inside of the cylinder below the under surface of the piston 11 to a conduit 14 through which air between the under surface of the piston and the corresponding surface of the cylinder will exhaust to the atmosphere when the piston 11 is being moved inwardly. A conduit 15 leads to the inside of the cylinder 10 above the piston 11 45 50 55

whereby fluid pressure may be delivered to and exhausted from the space between the upper surface of the piston and the corresponding surface of the cylinder to move the piston inwardly or permit its being moved outwardly as will be hereinafter more fully described.

A piston rod 16 forming a part of the piston 11 has a head or sliding member 17 rigidly attached to the extreme outer end thereof which is guided upon guide rods 18 and normally held in its outermost position, as shown in Figure 5, wherein the piston 11 is at the outermost end of the cylinder 10, by means of compression springs 19 also disposed on the guide rods 18 and adjustable as to tension by means of adjusting nuts 20 and by means of which the speed of outward travel of the head and piston may be regulated or controlled. With this construction, the piston 11 is normally moved inwardly by fluid pressure entering the cylinder through the conduit 15 whereby the springs 20 are compressed and is moved outwardly by the action of the compressed springs when the pressure above the piston is released.

The member or head 17 has a link 21 attached thereto, the opposite end of the link being pivotally secured to one end of an arm 22 that is pivoted as at 23 and forms an operating arm for rotating the turrets table 6. Trigger mechanism consisting of a trigger 24 that is normally held in its outermost position wherein it engages a pin 25 on each of the form supports by means of a spring 26 and is limited in its outward movement by a flat surface 27 which engages a flat surface on the arm 22 is carried by the opposite end of the arm from that end to which the link 21 is attached. Movement of the end of the arm 22 to which the link 21 is attached is controlled by an adjustable stop 28 whereby rotation of the arm 22 about its pivot may be regulated.

In the operation of this part of the apparatus, when the bed 5 which is in alignment with the ironing member 2 is out of ironing engagement with the member, the turrets operating mechanism just described is in the dot dash line position shown in Figure 3, wherein the trigger 24 is out of engagement with the pin 25. However, when the aligned form and ironing member are in ironing engagement, fluid pressure flows into the cylinder 10 above the piston 11 by way of the conduit 15 as will be hereinafter described to move the piston inwardly compressing or winding up the springs 19 and moving the arm 22 to the full line position shown in Figure 3 wherein the trigger 24 engages the pin 25, such trigger passing the pin 25 as the arm is rotated about its pivot in this direction due to its resiliency through its pivotal mounting and the spring 26.

Then, upon release of pressure from the outer surface of the piston 11 which takes place when the aligned form 5 is moved out of engagement with the ironing member 2, the springs 19 will move the head 17 and piston 11 outwardly with a quick action and rotate the arm 22 about its pivot, the trigger 24 through its engagement with the pin 25 of the form that is in alignment with the ironing member moving the form 5 out of alignment with the ironing member and the other form 5 into alignment therewith by rotating the turrets table 6 on the pedestal 8. As shown in Figure 2, a latching means consisting of a latch member 29 that is held in its uppermost position by means of springs 30 and a

latch pin 31 is provided for stopping the rotation of the turrets table 6 when one form 5 is in alignment with the ironing member 2 and holding that form in such aligned position, as well as holding the other form in loading position.

As shown in Figure 8, a cylinder and piston construction is provided immediately beneath the heated ironing member 2 in such position that the uppermost end 32 of a piston rod 33 that forms a part of a piston 34 in a cylinder 35 will contact with the under part of the shaft or rod 18 which is mounted immediately beneath the ironing forms 5, and move the form upward into engagement with the heated ironing member for the ironing action. The extending arms 7 of turrets table 6 are provided with a cylindrical sleeve 79 which provides a bearing for shaft or rod 18 of the ironing form, during its upward and downward movement. A guide rod 80 rigidly attached to ironing form 5 is provided and is disposed to move upward and downward through a sleeve provided in arm 81, thus always maintaining the ironing form in correct alignment with the ironing member.

As shown in Figure 5, fluid pressure for raising the piston 34 to move the aligned form 5 upwardly flows through a supply pipe 36, through a conduit 37, past a needle valve 38 for controlling the rate of flow of the fluid pressure, past a valve 39 which is operable by a foot treadle 40, and through a conduit 41 between the under surface of the piston 34 and the corresponding surface of the cylinder 35, the air or pressure between the upper surface of the piston 34 and the corresponding surface of the cylinder 35 exhausting through a conduit 42 and exhaust conduit 14.

Reversely, the piston 34 is moved downwardly by the weight of the form 5 resting thereon, the fluid pressure between the under surface of the piston 34 and the corresponding surface of the piston 35 exhausting through the conduit 41 and port 43 that is under the control of a foot treadle 44 and normally in open position, and to the atmosphere by way of the exhaust conduit 14.

In the preferred construction of the operating mechanism for the valve 39 which controls the supply of fluid pressure to the under surface of the piston 34 and the outlet valve 45 that controls the opening and closing of the port 43 and thereby the exhaust of fluid pressure from beneath the piston 34 to permit downward movement thereof, the arrangement is such that when the inlet valve 39 is opened the exhaust valve 45 will be simultaneously closed by action of a spring 43' on the operation of the single foot treadle 40. Likewise, the arrangement is such that when it is desired to lower the form out of ironing engagement with the heated ironing member 2, operation of the foot treadle 44 to cause opening of the port 43 by movement of the valve 45 will permit the valve 39 to be closed by action of a spring 39' whereby flow of fluid pressure to the under surface of the piston 34 is prevented, such opening of the valve 45 and closing of the valve 39 being effected by the operation of the single foot treadle.

As shown in Figure 7, the intake valve 39 is disposed in a housing 46 and has the upper end of its stem connected to one end of a pivoted lever arm 47, the other end of the lever arm carrying a roller 48 adapted to bear against the face of a cam element 49 that is disposed on one end of a lever arm 50 rigidly mounted on a shaft 51. The cam 49 is of such shape that the lever

arm 41 is turned so that the valve 39 is normally in closed position and the valve is moved to open position by means of the foot treadle 40 which has an extending portion thereof connected to one free end of the lever arm 59 by means of a link 52. After once being moved to open position, the valve 39 will be maintained therein by the roller 48 engaging a raised portion 53 on the cam.

10 In a like manner, the exhaust valve 45 disposed in a housing 45' and which is normally in closed position also, has its stem connected to one end of a lever arm 54 whose other free end carries a roller 55 engaging a cam 56 that is oppositely disposed as regards the cam 49 and is rigidly mounted on the same shaft 51. Such valve is moved to open position against the resistance of the spring 43' by depressing a foot treadle 44 which has a portion thereof connected to a crank arm 57 by means of a link 58. Another part of the crank arm 57 is, in turn, connected to the free end of the lever arm 59 which carries the cam 56 by means of a link 60. With this construction, depression of the foot treadle 44 will move the cam 56 upwardly, the cam being so shaped as to move the lever arm 54 about its pivot in a direction to open the valve 45. With the cams 49 and 56 oppositely disposed and rigidly mounted on the same shaft, it will be apparent that movement of one cam to open one valve will operate the other cam to close the valve controlled thereby or vice versa.

As shown in Figure 2, one part of the crank arm 57 is connected to a link 76 by means of a pin and slot connection, the other end of the link being connected to the latch 29 whereby downward movement of the foot treadle will cause the latch 29 to be moved downwardly against the resistance of the springs 30 so that the turreting table and forms will be released and the turreting table may be rotated in the manner hereinafter described on downward movement of the piston 34 and downward movement of the forms under their own weight.

45 Means have been provided for causing rotation of the turreting table 6 immediately on the form 5 which has been in ironing engagement with the ironing member 2 reaching its lowermost position. As shown in Figures 3 and 4, an auxiliary valve 61 controlling the flow of fluid pressure to the outer surface of the piston 11 whereby the piston is moved inwardly and the trigger mechanism set as hereinbefore described, is operable by the upward and downward movement of the form 5 which is in alignment with the ironing member 2 through a system of levers which each form engages as it moves into aligned position with the pressing member.

60 The means for operating the auxiliary valve 61 consists of a lever 62 pivoted to the frame as at 63 and having a slot and pin connection with another lever 64 which is pivotally mounted as at 65 to an upright 66 on another part of the frame by means of a slot 67 on the lever 64 and a pin 68 on the lever 62. A counterweight 69 is disposed on the extreme outer end of the lever 62 and such lever carries a stud 70 that projects laterally therefrom and is adapted to move into engagement with the bifurcated end of a yoke member 71 that is rigidly mounted on the support for each form 5 as at 71', see Fig. 3. The yoke member is curved generally as shown in this figure, having its curved jaws extending from the point 72' whereby the yoke may move out of engagement with the stud 70 as the form completes its cycle of

movement from alignment with the head to the loading and unloading station. Also, the lever 64 is connected to the upper end of the sliding portion 72 of the auxiliary valve 61 by means of a link 73.

In the operation of this part of the apparatus, which is a means for automatically causing rotation of the turreting table 6 as each form 5 reaches its lowermost position after ironing engagement with the ironing member 2, as each form 5 moves 10 into alignment with the ironing member 2 due to rotation of the turreting table 6, the stud or pin 70 engages the bifurcated end of the yoke member 71. Then, on the operation of the treadle 40 to open the inlet valve 39 and subsequent raising of the piston 34 and aligned form 5 as hereinbefore described, the yoke member 71 will move upwardly with the form and in doing so will engage the stud or pin 70 on the lever 62 and the levers 62 and 64 will be moved to the dash and 20 dot line position shown in Figure 4 during which movement the sliding portion 72 of the auxiliary valve 61 will be raised. In a reverse manner, when the aligned form 5 is permitted to lower under its own weight due to the operation of the 25 foot treadle 44 and release of pressure from beneath the piston 34 as hereinbefore described, the levers 62 and 64 will be moved to the full line position shown in Figure 4, wherein the sliding portion 72 of the auxiliary valve 61 will be moved 30 downwardly to the position shown in Figure 5, the weight 69 at the free end of the lever 62 being provided to assure the return of the levers 62 and 64 to their original starting position and the downward movement or closure of the sliding portion 72 of the auxiliary valve 61.

Upward movement of the sliding portion 72 of the valve 61 will permit fluid under pressure to flow from the supply pipe 36 past the cut away portion 71 of the sliding member and through 40 the conduit 15 into the cylinder 10 between the surface of the piston 11 and the corresponding surface of the cylinder 10 to move the piston inwardly as shown in Figure 3 to set the trigger mechanism and compress the springs 19 as hereinbefore described, any pressure on the opposite side of the piston exhausting through the conduit 13 and exhaust conduit 14. Thus, the setting of the trigger mechanism and compression of the springs 19 is automatically brought about by the 50 upward movement of the aligned form 5 into ironing engagement with the ironing member 2.

After the ironing operation is completed, the form 5 is lowered as hereinbefore described, and the auxiliary valve operating levers returned to 55 their normal position wherein the sliding member 72 is moved downwardly to the position shown in Figure 5 or to closed position, the fluid pressure that holds the piston 11 in such position that the springs 19 are compressed will exhaust 60 through the conduit 15, through a port 74 in the stem of the sliding member 72 and into the hollow interior thereof, through a conduit 75, and into the exhaust conduit 14 whereby the compressed springs 19 may act to rotate the turreting table 6 and reverse the position of the diametrically disposed forms 5 as hereinbefore described. The cycle just described is repeated at the movement of each individual form into alignment with the ironing member 2 and then 70 further movement of the aligned form into and out of ironing engagement with the heated ironing member 2.

With this construction, we have provided a device of the above type embodying operator op- 75

erated means which includes the foot treadles for operating the main valve for controlling the movement of the bed that is aligned with the ironing head into and out of ironing relation with the head and have provided means operating automatically which includes the slide valve 61 for moving the beds alternately into and out of ironing alignment with the ironing head as well as a latching means operable by the operator operated means which releases an ironing bed from engagement with the ironing head for holding the beds in their aligned position.

What we claim is:

1. Apparatus of the class described comprising a plurality of ironing beds mounted on supports in spaced relation about a point, an ironing head, means including a vertically disposed cylinder and piston construction positioned below the head and so arranged that the uppermost end of a piston rod carried by said piston will coat with the under side of an ironing bed in alignment therewith for moving an ironing bed upwardly into engagement with said ironing head, and means controlled by movement of said ironing bed out of engagement 25 with said ironing head for moving another bed into alignment with said ironing head.

2. Apparatus of the class described comprising a plurality of ironing beds mounted on supports in spaced relation about a point, an ironing head, means including a vertically disposed cylinder and piston construction positioned below the head and so arranged that the uppermost end of a piston rod carried by said piston will coat with the under side of an ironing bed in alignment therewith for moving an ironing bed upwardly into engagement with said ironing head, means controlled by movement of said ironing bed out of engagement with said ironing head for moving another bed into alignment with said ironing head, and latching means for maintaining said ironing beds in their respective positions.

3. Apparatus of the class described, comprising a plurality of ironing beds mounted on a rotatable support in spaced relation about a point, an ironing head, means for moving a registered ironing bed into engagement with said ironing head, and means controlled by movement of said registered ironing bed out of engagement with said ironing head for moving said bed out of registry therewith, said bed moving means including a trigger mechanism set by movement of said registered bed into ironing engagement with said head and released by movement of said registered bed out of engagement with said head.

4. Apparatus of the class described, comprising a head member, a rotatable frame having a plurality of bed members thereon adapted to be carried by frame rotation into and out of registry with said head member, means for producing relative ironing movement between said head and bed members when in registry, frame rotating mechanism, and control means therefor operable by relative approach and separating movement of said members to produce operation of said mechanism and frame rotation, said control means including means for vitalizing the frame rotating mechanism by relative approach movement of said members, and means for rendering said frame rotating mechanism effective as a frame rotating means by relative separating movement thereof.

5. Apparatus of the class described, comprising a rotatable frame, a plurality of ironing beds in spaced relation thereon, an ironing head above the path of rotating movement of the beds, means including a vertically arranged piston positioned

below the head whereby to coat with a bed in registry with said head for moving the bed upwardly into engagement with said head, and frame rotating mechanism including a piston set trigger mechanism and a controlling valve therefor, said valve being operable by movement of a bed into and out of engagement with said head to produce setting and operation of said trigger mechanism to rotate said frame and bring successive beds into registry with said head.

6. Ironing apparatus, comprising a head member, a movable frame, a plurality of bed members on said frame adapted to be carried by frame movement into and out of registry with said head member, means for producing relative ironing approach movement between said head and a bed member in registry therewith, and frame moving mechanism including a spring, means for placing and maintaining said spring in stressed condition by relative approach movement of said head and a bed in registry therewith, means for releasing said spring by relative separating movement of said head and bed, and a connection between said spring and said frame.

7. Ironing apparatus, comprising a head member, a rotatable frame, a plurality of bed members on said frame adapted to be carried by frame rotation into and out of registry with said head member, means for producing relative ironing approach movement between said head and a bed member when in registry, and frame rotating mechanism including a spring, means for placing and maintaining said spring in stressed condition by relative approach movement of said head and a bed in registry therewith, means for releasing said spring by relative separating movement of said head and bed, and a connection between said spring and said frame including a trigger mechanism set by relative approach movement of said head and bed.

8. Apparatus of the class described, comprising a head member, a frame rotatable in a horizontal plane and provided with a plurality of bed members adapted to be carried by frame rotation into and out of registry with said head member, means for producing relative ironing movement between said head member and a bed member in registry therewith, and means actuated by said relative ironing movement of said head and bed members for causing rotation of said frame.

9. Apparatus of the class described, comprising an ironing head, a plurality of ironing beds mounted on a frame and movable selectively into registration beneath the head, means including a vertically disposed cylinder and piston construction positioned below the path of travel of the beds and having an operative connection arranged to coat with an ironing bed in registering position for moving said bed vertically into engagement with said ironing head, and means actuated by vertical movement of said bed for moving another bed into alignment with said ironing head.

10. Apparatus of the class described, comprising an ironing head, a plurality of ironing beds mounted on a frame and movable selectively into registration beneath the head, means including a cylinder and piston construction positioned below the path of travel of the beds and having an operative connection arranged to coat with an ironing bed in registering position for moving said bed vertically into engagement with said ironing head, and means actuated by

vertical movement of said bed for moving said bed out of registering position.

11. Apparatus of the class described, comprising a head member, a movable frame having a plurality of bed members thereon adapted to be carried by frame movement selectively into and out of registry with said head member, means for producing relative approach and separating movement of said registered head and bed members, frame moving mechanism, and control means therefor including means for vitalizing said mechanism by relative approach movement of said members, and means for rendering said vitalized mechanism effective to move the frame by relative separating movement of said members.

12. A pressing machine comprising a movable pressing member arranged to travel freely along a substantially horizontal path, a fixed pressing member adjacent said path and arranged to contact to perform a pressing operation with said movable member when said members are in registry, power means operative to kick said movable member a short distance along said path, the parts being so arranged that said movable member leaving said power means travels by its own momentum an additional distance along said path into registry with said fixed pressing member, and means to effect said pressing operation when the members are in registry.

13. Apparatus of the class described, comprising a head, a bed movable in a horizontal plane into and out of registry with said head and mov-

able vertically into and out of ironing engagement therewith, means for moving said bed in said plane, means for moving said bed vertically, and operative connections between the two means for vitalizing the first named means when the second-named means moves in into-engagement direction and for rendering said vitalized means effective to move the bed when the second-named means moves in out-of-engagement direction.

14. In a pressing machine, an ironing head, a 10 rotatable structure including a bed movable by structure rotation into and out of registry with said head, power means for lifting said registering bed into engagement with said head, means for releasing said power means whereby said bed 15 is free to descend, means cooperating with said structure during descent of said bed for rotating said structure to move said bed out of registry, and said last named means being put in operative condition to perform its function during the 20 bed lifting operation of said power means.

15. In a pressing machine, a pressing head, a rotatable frame, a pressing bed movable by frame rotation into and out of registry with said head, power means adapted to raise said bed 25 when in registration into engagement with said head, frame rotating means, and means rendering said frame rotating means effective by movement of said bed upward and then downward as it moves into and out of engagement with the 30 head.

CHARLES M. OTIS.
ALEXANDER K. DEAN.
